UNITED STATES PATENT OFFICE.

JOHN GRAVES, OF MADISON, WISCONSIN, ASSIGNOR TO FRENCH BATTERY & CARBON CO., OF MADISON, WISCONSIN, A CORPORATION OF WISCONSIN.

EJECTING MECHANISM FOR CORE-MAKING MACHINES.

1,305,279.

Specification of Letters Patent.

Patented June 3, 1919.

Application filed January 25, 1919. Serial No. 273,184.

To all whom it may concern:

Be it known that I, JOHN GRAVES, a citizen of the United States, residing at Madison, in the county of Dane and State of Wisconsin, have invented a certain new and useful Improvement in Ejecting Mechanism for Core-Making Machines, of which the following is a specification.

This invention relates to machines for making cores in which material to be molded is tamped by a machine into a suitable mold, from which the finished product is ultimately ejected by the machine. The object of the invention is to provide a machine of this class which is very simple in construction, which can be easily and cheaply made, which is satisfactory in operation and is not readily liable to get out of order.

The invention consists in combination with an ordinary mold having a plunger which forms its bottom during the molding operation and its ejecting mechanism thereafter, of mechanism by which the plunger remains at all times stationary while the mold is moved bodily with reference to the plunger to eject the contents of the mold. The invention further consists in many features and details of construction which will be hereafter more fully set forth in the specification and claims.

Referring to the drawings, in which similar numerals indicate the same parts throughout the several views,

Figure 1 is a side elevation partly in section of mechanism illustrating the invention in its preferred form.

Fig. 2 is a sectional view through the mold mechanism taken from the left hand side of Fig. 1.

Fig. 3 is a plan detail view taken on the irregular line 3—3, of Fig. 1.

As shown in the drawings, the machine is carried on a table frame 10, having rising from it a column 12, the whole supported from any suitable standard, not shown in the drawing.

Depending from the table 10, heretofore referred to, is a bracket 14 carrying at its bottom a front lug 16 and a rear lug 18. Adjustably secured in the front lug 16 by suitable nuts 20 and 22 is a stationary plunger 24, whose upper end 26 forms the bottom of the concentric mold 28 within which the core to be formed is tamped. This mold 28 is embraced by a clamp 30 which is in

turn rigidly secured by screws 32 on a cross-head member 34 reciprocatable in vertical guides 36, formed in the bracket 14. The upward vertical movement of the crosshead 34 with reference to the plunger 24 is regulated and controlled by adjustably positioned screws 38, shown in detail in Fig. 1, these screws themselves being slidable through the frame bracket member 10—14.

As clearly shown in Fig. 3, bracket 14 is cast so as to form two parts, through which is a shaft 40 on which, between the parts of the bracket, is mounted the bifurcated lever 42 which straddles member 24 and is pivoted to crosshead 34 on the pins 46, clearly shown in Fig. 3. Similarly, the opposite end of lever 42 straddles vertical rod 48 and to its separated extremities are attached springs 50, in turn connected to a collar 52 on the lower end of member 48. The result of this construction is that so long as the parts are in the position of Fig. 1, the springs 50, just described, serve to sustain the rod 48 in the position shown in the drawings, with the tamping tool 54 thereon in the position shown in Fig. 1 clear of the mold 28. The mechanism at the upper end of rod 48 for reciprocating tool 54 to perform the tamping operation is fully shown, described and claimed in my co-pending application, Serial No. 273,183, filed herewith, and as it forms no part of this particular invention, is not further shown, described or claimed herein.

Connected to lever 42 by means of a pin 56 is a rod 58, reciprocatable through bracket 16, as shown in Fig. 1. This rod 58 is surrounded by a spring 60 which serves the function of normally holding lever 42 in the position shown in Fig. 1 with the mold 28 in the normal position above the end 26 of plunger 24 so that the molding mechanism is ready to receive material to be tamped.

As is fully shown, described and claimed in my copending application above referred to, the tamping operation proper is effected by rotating hand-lever 62 and shaft 64 in a counter-clockwise direction from that shown in Fig. 1. As the upper end of rod 48 is attached to crosshead 66 which is driven through rack and pinion mechanism 68 in a downward direction during this tamping operation, it will be seen that the rod 48 is thus moved downward against the action of springs 50. The possible amount of such motion is measured by the distance between

bracket 18 and adjustable collar 70 on rod 48. This movement takes place without the motion of rod 48 in any way affecting lever 42 or mold 28.

- 5 When, however, the operator moves lever 62 about shaft 64 in a clockwise direction as far as rack and pinion member 68 will permit, rod 48 moves substantially upward so that collar 70 strikes the lower adjacent end 10 of lever 42 and rotates that lever in a counter-clockwise direction against the action of spring 60, thus moving crosshead 34 and mold 28 downward with reference to plunger 24 a sufficient distance to eject the contents of the mold so that it can be removed 15 from the machine.

It will be noticed that by properly manipulating the nuts 20 and 22, the plunger 24 may be adjusted easily and quickly up 20 and down in the mold 28 to accommodate cores of different heights. This adjustment is much simpler than where it is attempted to either adjust an entire mold or substitute a different mold. A further advantage lies in 25 the fact that by lowering the mold to eject the finished product, more room is obtained for the hand of the operator between the mold and the tamping tool 54 than is ever possible where the mold is stationary and the 30 finished product is ejected from it.

Having thus described my invention, what I claim as new and desire to secure by Letters Patent, is:-

1. In mechanism of the class described, a 35 reciprocatable tamping tool, a normally fixed plunger in line with the tamping tool, a mold for material to be tamped so located that said plunger forms its bottom, and mechanism for moving the mold member 40 along said plunger away from the tamping tool, for the purposes set forth.

2. In mechanism of the class described, the combination with a suitable supporting frame, a tamping tool reciprocatable with 45 reference to the frame, a plunger member in line with the tamping tool, a mold member embracing the plunger member and movably mounted with reference thereto, a single operating mechanism connected to the tamping member and to the mold member adapted to, in moving in one direction, reciprocate the tamping member without affecting the mold and when moved in the opposite direction, withdraw the mold member along 50 the plunger away from the tamping member to eject the product from the mold.

3. In mechanism of the class described, the combination with a suitable support, a plunger member, a mold member inclosing the plunger member in such a way that the plunger member forms a bottom for the mold during the molding operation, spring mechanism holding the mold member normally in said position, and means for mechanically withdrawing the mold member 60

against said spring holding mechanism to cause the plunger member to eject the contents from the mold.

4. In mechanism of the class described, a vertically mounted plunger member, a mold member reciprocatable along said plunger member, and spring mechanism normally holding said mold mechanism in a position where the plunger forms the bottom of the mold during the molding operation. 75

5. In mechanism of the class described, a vertically mounted plunger member, a mold member reciprocatable along said plunger member, spring mechanism normally holding said mold mechanism in a position where 80 the plunger forms the bottom of the mold during the molding operation, and hand operated mechanism for moving the mold member against said spring action to a point where the plunger member ejects the contents of the mold. 85

6. In mechanism of the class described, a vertically mounted plunger member, a mold member reciprocatable along said plunger member, spring mechanism normally holding 90 said mold mechanism in a position where the plunger forms the bottom of the mold during the molding operation, and means adjustably controlling the limit of the upward movement of the mold with reference 95 to the plunger.

7. In mechanism of the class described, a vertically mounted plunger member, a mold member reciprocatable along said plunger member, spring mechanism normally holding 100 said mold mechanism in a position where the plunger forms the bottom of the mold during the molding operation, and adjustable screw-mechanism controlling the limit of upward movement of the mold with reference 105 to the plunger.

8. Mechanism of the class described, the combination with a suitable support, a mold member reciprocatably mounted with reference to the support, a central plunger 110 member for the mold, normally stationary with reference to the support, means for selectively adjusting the position of the plunger member with reference to the support, and means for reciprocating the mold 115 member with reference to the plunger to thereby cause the plunger to eject the contents of the mold.

9. In mechanism of the class described, the combination of a suitable frame, a mold member mounted for reciprocation vertically of said frame, a plunger member normally rigid on the frame, normally forming the bottom of said mold, a generally horizontal lever pivoted to the frame and 120 connected to the mold mechanism, spring mechanism normally moving said lever to hold said mold in such a position that the plunger forms the bottom of the mold, and manually operated means carried by the 125 130

frame for moving said lever contrary to the action of said spring, for the purposes set forth.

10. In mechanism of the class described, the combination of a suitable frame, a mold member mounted for reciprocation vertically of said frame, a plunger member normally rigid on the frame, normally forming the bottom of said mold, a generally horizontal lever pivoted to the frame and connected to the mold mechanism, spring mechanism normally moving said lever to hold said mold in such a position that the plunger forms the bottom of the mold, a reciprocatable tamping mechanism coöperating with said mold, means movable in one

direction to cause said tamping mechanism to tamp material in said mold, and means connected to said operating mechanism and to said lever operable only when the operating mechanism is manipulated in the opposite direction from that heretofore set forth to retract the mold along the plunger to eject the product from the mold.

15 In witness whereof, I have hereunto subscribed my name in the presence of two witnesses.

JOHN GRAVES.
